UNITED STATES PATENT OFFICE.

MAX KÖHLER, OF LIMBACH, GERMANY.

THREAD-TENSION MECHANISM FOR SEWING MACHINES.

Application filed February 12, 1927. Serial No. 167,628.

The present invention relates to an improvement in sewing machines and more particularly to the mechanism for maintaining predetermined conditions of tension on the thread or threads used in said machines. One object of the present invention has been to provide tension mechanism particularly adapted for use on a sewing machine of the over-seaming type in which separate threads are used, one for the looper and one for the needle. It is also an object of the present invention to provide a tension mechanism from which spring control has been eliminated and in which the desired degree of tautness or looseness of the thread with respect to the needle and looper will be afforded by operation of positively actuated guiding agencies. A further object of the invention has been to provide in an over-seaming machine tension mechanism by means of which the tension on the looper and needle threads respectively will be properly balanced and related to permit the most rapid and effective operation of said looper and needle.

One embodiment of my invention is illustrated in the drawings accompanying the present specification and in which

Figure 1 is a front view with portions of the casing broken away and with portions shown in vertical section, and

Figure 2, a side view with portions of the casing broken away and interior portions shown in vertical section.

As indicated in the drawings, a preferred form of my improved tensioning mechanism is associated with a sewing machine of well known type and including a looper 1 and a needle 2, mounted on carriers 3 and 4 respectively, both of which are driven from a central or driving shaft 5 by any suitable connecting means not shown. A needle thread 6 and a looper thread 7 engage the needle 2 and the looper 1 respectively and, in normal operation of the feed mechanism are withdrawn from suitable supporting means of any well known type, such as spools, conveniently mounted on the framework of the machine or otherwise, it being deemed unnecessary to show the same.

The tension of both threads 6 and 7 is controlled by similar means. For example, as to thread 6, the web thereof engages fixed guides 8 and 9 between which is positioned a friction guide 10, said guides being con-

veniently mounted on a bracket 11, which also supports guides 12, 13 and 14, corresponding respectively to the guides 8, 9 and 10 positioned to operate on thread 7. A thread conduit 15 extends through the front wall of the machine and extends downwardly toward the needle 2 and in position to deliver thereto the forward end of thread 6. Between said conduit 15 and the fixed guide 9 are positioned spaced guides 16 and 17, having thread receiving recesses therein. A cam or take up 18 mounted on shaft 19 is grooved peripherally to form spaced peripheral thread engaging surfaces and is positioned to rotate between said spaced guides 16 and 17. A fixed guide 20 has one end extending between the thread engaging surfaces of cam 18 and is provided with a thread guiding slot whereby the extent of movement of the thread in the direction of rotation of the cam is effectively limited.

The shaft 19 also carries a cam or take up 21 positioned between spaced guides 22 and 23. A slotted guide 24 is positioned with its slotted end projecting into the groove of the cam 21 and serves a purpose with respect to thread 7 similar to that served by the guide 20 with respect to thread 6.

A spur gear 25 is mounted on shaft 19, being actuated from the driving shaft 5 by any suitable connection such, for example, as a shaft 26 having a pinion 27 engaging the gear 25 and the pinion 28 engaging a gear 29 mounted on shaft 5. Motion of rotation is imparted to shaft 5 by any suitable means, such as a belt connected to the fly wheel 30 and not shown.

In operation the looper 1 is given a combined reciprocatory and oscillating movement common to machines of the type described while the needle 2 is given a reciprocatory movement, all movements preferably being taken from shaft 5. The thread with drawing mechanism which comprises the feeding and loop forming devices, withdraws both threads in characteristic intermittent manner. As the thread 6 is being drawn forward by forward movement of the needle 2, for example, it should run freely but without undue looseness. At a different stage of the sewing operation, it is desirable to form a loop adjacent to the end of the needle so that the looper may engage properly, these considerations being well understood by persons skilled in the art. To afford a basic re-

- sistance to forward movement of the threads, the latter are passed over or into engagement with the friction devices 10 and 14 which exert a constant frictional resistance to passage of said threads, while cams 18 and 21 respectively encounter their corresponding threads and impart thereto varying degrees of displacement from the normal path as fixed between the spaced thread guides 16 and 17 and 22 and 23 respectively. It will be apparent that cams 18 and 21 during a portion of their rotation tend to retard or prevent the formation of slack in their respective threads whereas other parts of said cams tend to release said threads so that a greater looseness or slackness thereof will be available for the loop forming operation. It is believed that the tension mechanism hereinabove described provides a positive thread tension control which is not only more effective in operation than well known forms of spring tension control, but also shows superior results in that the thread tensioning means of both looper and needle are synchronized with the thread withdrawing means, whereby accurate operation of ma-

chines of this type is more nearly accomplished. Other advantages flowing from practicable applications of my invention will be apparent from a consideration of the details of construction of the embodiment described in the foregoing specifications and illustrated in the drawings.

I claim as my invention:

Looper and needle thread tensioning mechanism for sewing machines, comprising a main drive shaft, a cam shaft operatively connected therewith, a set of spaced thread guides for the looper thread, a set of spaced thread guides for the needle thread, a pair of take up cams on said cam shaft, one of said cams being positioned to rotate across the path of said looper thread between said looper thread guides, and the other cam being positioned to rotate across the path of said needle thread between said needle thread guides.

In testimony whereof, I have signed my name to this specification this 27th day of January, 1927.

MAX KÖHLER.
